(57) **CLAIM**

The ornamental design for a handlebar grip as shown and described.

DESCRIPTION

FIG. 1 is a front isometric view of a handlebar grip in its environment.

FIG. 2 is a second isometric view of the handlebar grip.

FIG. 3 is a first side elevation view of the handlebar grip of FIG. 2.

FIG. 4 is an opposite side elevation view of the handlebar grip of FIG. 2 opposite that of FIG. 3.

FIG. 5 is a front elevation view of the handlebar grip of FIG. 2.

FIG. 6 is a rear elevation view of the handlebar grip of FIG. 2.

FIG. 7 is a top plan view of the handlebar grip of FIG. 2; and, FIG. 8 is a bottom plan view of the handlebar grip of FIG. 2.

The handlebar grip is shown with a symbolic break in its length. The appearance of any portion of the article between the break lines forms no part of the claimed design. The broken line showing of a handlebar is for the purpose of illustrating environmental structure and forms no part of the claimed design.
